UNITED STATES PATENT OFFICE.

REUBEN HEGARTY, OF MADERA, PENNSYLVANIA.

MEASURING-POLE.

SPECIFICATION forming part of Letters Patent No. 595,475, dated December 14, 1897.

Application filed April 30, 1897. Serial No. 634,639. (No model.)

To all whom it may concern:

Be it known that I, REUBEN HEGARTY, of Madera, in the county of Clearfield and State of Pennsylvania, have invented certain new and useful Improvements in Measuring-Poles; and I do hereby declare the following to be a full, clear, and exact description of the invention, such as will enable others skilled in the art to which it appertains to make and use the same.

This invention is an improvement in lineal measures, and especially in poles or rods which are made extensible longitudinally.

My improved measuring-pole is hereinafter described, and the novel features are specifically indicated.

In the accompanying drawings, forming part of this specification, Figure 1 is a perspective view of a portion of a measuring-pole constructed in accordance with this invention. Fig. 2 is a longitudinal section. Fig. 3 is a cross-section; and Figs. 4 and 5 are cross-sections, on an enlarged scale, of the two sections of the measuring-pole.

I construct my improved measuring-pole of longitudinal sections or members, which are so connected as to be adapted to slide one on another and which have no projecting parts.

In the drawings, 1 and 2 indicate the members of the pole, which are generally rectangular in cross-section, and therefore when secured together present also a rectangular figure. These sections or members of the pole are held together against lateral play, but capable of longitudinal movement, by means of a guide 3 upon member 1 and a slide 4 upon member 2. The slide and guide are so made that when they coat the adjacent faces of the members are in contact with each other, as shown, to present not only a finished device, but to prevent the entrance of dirt or particles between the sliding poles of the two members.

In the particular construction illustrated the face of the member 1 is provided with a longitudinal groove 5, in which the guide 3 is situated, said guide consisting, preferably, of a sheet-metal piece having overhanging flanges 6 in the manner shown. In the particular construction illustrated these over-

hanging flanges 6 of the guide stand slightly beyond the face of the member 1, as shown.

The member 2, upon which the slide 4 is secured, is provided with a central rib 7 on 55 its inner face, which stands a little beyond the edges of the member. On each side of this rib 7 are grooves 8, while the slide 4, which consists of a strip of sheet metal, is secured upon its rib and projects over the 60 grooves 8 and almost to the outer sides thereof. In this way it is seen that between the outer edges of the slide 4 and the grooves a pocket is formed, which receives the flanges 6 of the guide. These parts are so made that 65 a close and tight fit is secured, which holds the two members of the pole together and in the position illustrated, and while relative lateral movement is effectually prevented the parts can move longitudinally, as is obvious.

For holding the members rigid with relation to each other I employ a spring-actuated detent 9, that is situated within a suitable recess 10 in said member 2. This detent is 75 pivoted between its ends and lies entirely within the recess—that is to say, there are no parts which project beyond the face of the member 2. One end of this detent is provided with a finger-piece 11, beneath which 80 the spring 12 is situated, while the other end of the detent carries a pin 13, that extends through an opening in the slide 4. The guide 3 is provided with a series of openings 14 to receive said pin 13 and thus hold the members 85 with relation to each other. Of course the distance between the openings 14 can vary as desired, while, for instance, it may be one foot. Devices are also provided for holding the members at any other point, which consists of a thumb-screw 15, passing through a screw-threaded opening 16 in the member 2 and through the slide 4, while the head of the thumb-screw is situated in a recess 17 in said member. By means of this thumb-screw the 90 two members can be wedged together at any point.

It will be seen from the foregoing description that I provide an extremely simple and durable measuring-pole, which is compact 100 and comprises the minimum of parts, which are not liable to get out of order, while the

entire device is so constructed that it has the appearance of two rectangular pieces of wood secured together—that is to say, there are no projecting thumb-screws, bearings, or clamps, 5 usually employed in devices of this character.

Having thus described my invention, what I claim as new, and desire to secure by Letters Patent, is—

- 10 o A measuring - pole consisting of the longitudinally-sliding members secured together and provided with a detent for holding the same immovable at intervals, and a thumb-

15 screw passing through one of said members and adapted to engage the other of said members, the head of said thumb - screw being situated within a recess in the member to which it is secured.

20 In testimony whereof I have signed this specification in the presence of two subscribing witnesses.

REUBEN HEGARTY.
